LOCK FOR DOORS OR OTHER CLOSURES

Alfred H. Groeger, New Hyde Park, N. Y., assignor
to Kason Hardware Corporation, Brooklyn,
N. Y.

Application October 17, 1952, Serial No. 315,255

11 Claims. (Cl. 292—92)

1

This invention relates to locks for doors or other closures, and, more particularly, to locks for refrigerator doors. The particular embodiment of the present invention, which is illustrated in the drawings and which will be described hereinafter in greater detail, comprises generally, a base fixed to the door, a yieldable latch on the base and engageable with a keeper on the door jamb, a movable handle on the base for moving the latch away from the keeper, and means for locking the handle to prevent movement thereof.

It is well known that thieves sometimes enter a store or warehouse which has a refrigerator and force the proprietor or other person into the refrigerator, and then lock the refrigerator door by dropping a headed pin through registerable openings in the handle and base, whereby the handle is prevented from moving. Under these circumstances, in the devices of the prior art, it is impossible to unlock the refrigerator door from the inside without removing the door or dismantling the lock. To perform such operation under conditions of extreme cold has often proved to be impossible. While the prior art shows such bars and other means for retracting the latch from the inside of the door, the problem of quickly and easily opening the door from the inside when it has been locked from the outside, as by a padlock or pin, has not been satisfactorily solved by the prior art.

It is, therefore, a principal object of the present invention to provide a simple and efficient means for retracting the latch from the inside of the refrigerator even if the handle is locked in place by the insertion of a pin, nail, or even a padlock through the registering opening in the handle and in the lock base.

It is another object of the present invention to provide a door lock which will serve under ordinary circumstances as a yieldable latch, and have the additional feature of emergency release when needed.

It is still another object of the present invention to provide a door lock which may be locked by a padlock or pin, which prevents retraction of the latch bolt by means of a "jimmy" or other tool.

It is still another object of the present invention to provide a door lock having the characteristics mentioned in the foregoing paragraph in which the latch bolt is actuatable independently of the handle and from the inside of the door.

It is a further object of the present invention to provide a door lock of the type described which is characterized by its simplicity and durability, which is effective for its intended purposes, and

2

which can be manufactured and sold at a reasonable cost.

Other objects of the present invention will become apparent upon reading the following specification and referring to the accompanying drawings, which form a material part of this disclosure.

The invention accordingly consists in the features of construction, combinations of elements, and arrangements of parts which will be exemplified in the construction hereinafter described and of which the scope will be indicated by the appended claims.

In the drawings:

15 Fig. 1 is a side elevational view of a device constructed in accordance with the present invention;

Fig. 2 is a view similar to Fig. 1 but in section, and showing a locking pin in position and the push bar extending through the door;

Fig. 3 is a sectional view taken on the line 3—3 of Fig. 2;

Fig. 4 is a sectional view taken on the line 4—4 of Fig. 2;

25 Fig. 5 is a sectional view taken on the line 5—5 of Fig. 2; and

Fig. 6 is a top plan view of the device.

Referring now more particularly to the drawings, 10 designates a refrigerator door and 11 a door jamb for the door. The door has outer and inner surfaces 12 and 13, respectively, and an edge portion 14 which overlaps the door jamb 11. Attached to the portion 14 by any suitable means is a rubber gasket 15 which abuts the door jamb 11 when the door is in closed position. The door is also provided with a transverse opening 16 extending therethrough for a purpose to be described hereinafter.

On the outer surface 12 of the door 10 is mounted the lock, generally designated 20, of the present invention. The lock 20 includes a base 21 having laterally extending flanges 22 and 23 and provided with a cored under surface 24a. The laterally extending flanges 22 and 23 are provided with spaced apertures or bolt holes 24, 25, 26 and 27 through which fasteners may be passed to secure the base to the door 10 with the under-surfaces 24 facing the outer surface 12 of the door. The base 20 is arranged with its forward end 28 adjacent the overlapping portion 14 of door 10 and is formed adjacent the end 28 with a pair of transversely spaced upstanding ears 29 and 30. Extending rearwardly from the ears 29 and 30 are side walls of reduced height 31 and 32 which rise adjacent the rearward end of the base

21 to form another pair of transversely spaced upstanding ears 33 and 34. The ears 29 and 30 are joined forwardly by the portion 35, and the ears 33 and 34 are joined rearwardly by the portion 36.

Intermediate the ends of base 21 and the side walls 31 and 32 and spaced from the latter, is a transversely disposed upstanding wall 40 having an aperture 41 extending therethrough. Forwardly of the wall 40 between the side walls 31 and 32, the base 21 is shaped to form a cylindrical supporting surface 42, there being an opening 43 extending through the latter surface. Rearwardly of wall 40 the side walls 31 and 32 are widened as at 44 and 45, whereby the space therebetween is reduced. Extending through the base 21 in registry with the opening 46 is an aperture 46 which opens into the space between wall portions 44 and 45. In the space between wall portions 44 and 45, contiguous thereto extending therealong are spaced slots 47 and 48 for a purpose to be described hereinafter.

Adjacent the forward end 28 of the base 21 and extending therethrough is a latch or latch bolt 50 having its projecting end 51 adapted for engagement with a keeper (not shown). The latch bolt 50 is slidable in the cylindrical surface 42 and provided with a transversely extending through opening 43. The latch bolt 50 is reduced rearwardly as at 54, thereby forming a shoulder 55. Rearwardly beyond the portion 54 the latch bolt 50 is further reduced to form a rectangular bar 56 which extends slidably through the opening 41 in wall 40 and is formed at its rearward end with spaced extensions 57 and 58.

A latch bolt extension bar 60 is arranged between side wall portions 44 and 45 and spaced therefrom, and is provided with a reduced forward extension 61 positioned intermediate the extensions 57 and 58 and pivotally connected thereto by pin 58'. In this manner the latch 50 articulated intermediate its ends.

Arranged above the reduced portions 54 and 56, and the latch bar extension 60 is a shell 65. The shell is provided with a top wall 66 extending along the upper edges of side walls 31 and 32, and side wall portions 44 and 45. Depending from top wall 66 of shell 65 are side walls 67 and 68. The shell side walls extend along the side walls 31 and 32 on opposite sides of the wall 40 and are bent inwardly at portions 69 and 70. The portions 69 and 70 extend downwardly and forwardly and are integral with the rearwardly extending shell wall portions 71 and 72. The lower edge of the portions 71 and 72 extend into the slots 47 and 48. Thus, the shell 65 substantially encloses the latch bolt in the base 21.

Arranged over the shell 65 is a handle 75 having a depending extension 76 extending between ears 29 and 30 and into the opening 53. The forward end of the handle 75 is pivotally secured to the ears 29 and 30 by the rivet or pin 77 and is secured to the shell 65 by the screw 78. The rearward end of handle 75 extends downwardly at 75' between the ears 33 and 34 and is secured between the rearwardly extending walls 71 and 72 of the shell 65 by rivet 79. Thus, the handle 75 and shell 65 will swing outwardly together about the pin 77, and the depending extension 76 will bear against the rear wall of opening 53 to move the latch bolt toward its retracted position. Resistance to retraction of the latch bolt is provided by a spring 80 which is circumscribed about the portions 54 and 56 and has its oppo-

site ends engaging the shoulder 55 and wall 40. Thus, it is seen that upon swinging movement of the handle 75 about the pin 77, the extension 76 will actuate the latch bolt 50 which will be retracted and the door may be opened.

Upon the inner side 13 of door 10 is a bushing 85 arranged in registry with the aperture 16 and secured to the door by fasteners 86. Extending through the bushing 85 and openings 16 and 46 is a push bar or rod 87 which is provided on its inwardly projecting end with a knob 88. The other end 89 of push bar 87 is adapted for engagement with the latch bolt extension 60 upon outward sliding movement of the push bar. A pair of aligned apertures 90 and 91 are formed in the side wall portions 44 and 45 just rearwardly of the latch bolt extension 60 when the latch bolt extension is in its extended or most forwardly position. It is apparent that when the latch bolt 50 is in its extended or latching position, a pin, padlock, or other elongated member, not shown, extending through the openings 90 and 91 would serve as stop means to prevent retraction of the latch bolt and unlocking of the door. That is, the handle 75 could not be pivoted, and the latch bolt 50 would be locked and could not be jimmied.

However, latch bolt 50 may be quickly and easily shifted to its retracted position by a person 30 on the inside of the door 10. Merely pushing the push bar 87 outwardly causes the latch bolt extension 60 to pivot about pin 58' at its forward end and ride over the pin or padlock in the openings 90 and 91 and release the latch bolt 50 from its locked condition. Further outward movement of the push bar 87 causes the latch bolt extension 60 to engage with the rearward depending end 76' of handle 75 and rotate the handle 75 and shell 65 about the pivot pin 77 to thereby retract the latch 50.

Of course, under normal conditions of use the above described device will serve as a spring pressed door latch in the usual manner.

It is apparent from the foregoing that there 45 is provided a device by which the several objects of this invention are achieved and which is well adapted to meet the conditions of practical use.

As various possible embodiments might be made of the above invention, and as various 50 changes might be made in the embodiment above set forth, it is to be understood that all the matter herein set forth in the accompanying drawings is to be interpreted as illustrative and not in a limiting sense.

Having thus described the invention, I claim as 55 new and desire to protect by Letters Patent of the United States:

1. A lock for a door comprising a base adapted to be secured to the outside of a door, a latch 60 mounted in said base for back and forth movement from a retracted position to an extended position for engagement with a keeper, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, and release means operable from the inside of 65 said door for consecutively disengaging said latch and abutment members and moving the other end of said handle to effect the movement of said latch to its retracted position.

2. A lock for a door comprising a base adapted

to be secured to the outside of a door, a latch mounted in said base for back and forth movement from a retracted position to an extended position for engagement with a keeper, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, and release means operable from the inside of said door for consecutively disengaging said latch and abutment members and moving the other end of said handle to effect the movement of said latch to its retracted position, said actuating means comprising an extension on said handle and engageable with said latch.

3. A lock for a door comprising a base adapted to be secured to the outside of a door, a latch mounted in said base for back and forth movement from a retracted position to an extended position for engagement with a keeper, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, release means operable from the inside of said door for consecutively disengaging said latch and abutment members and moving the other end of said handle to effect the movement of said latch to its retracted position and a pair of aligned holes in said base, said abutment member being insertable in said holes.

4. A lock for a door comprising a base adapted to be secured to the outside of a door, a latch mounted in said base for back and forth movement from a retracted position to an extended position for engagement with a keeper, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, and release means operable from the inside of said door for consecutively disengaging said latch and abutment members and moving the other end of said handle to effect the movement of said latch to its retracted position, said release means comprising a push bar extending through said door and engageable with said latch.

5. A lock for a door, comprising a base adapted to be secured to the outside of a door, a latch mounted in said base for back and forth movement from a retracted position to an extended position for engagement with a keeper, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, release means operable from the inside of said door for consecutively disengaging said latch and abutment members and moving the other end of said handle to effect the movement of said latch to its retracted position, and a pair of aligned holes in said base, said abutment members being insertable in said holes, said release

means comprising a push bar extending through said door and engageable with said latch.

6. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, and release means operable from the inside of said door for consecutively moving the inner articulated end of said latch out of engagement with said abutment member and moving the other end of said handle to effect the movement of said latch to its retracted position.

7. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, and release means operable from the inside of said door for consecutively moving the inner articulated end of said latch out of engagement with said abutment member and moving the other end of said handle to effect the movement of said latch to its retracted position, said actuating means comprising an extension on said handle and engageable with said latch, and spring means urging said latch toward its extended position of movement.

8. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, release means operable from the inside of said door for consecutively moving the inner articulated end of said latch out of engagement with said abutment member and moving the other end of said handle to effect the movement of said latch to its retracted position and a pair of aligned holes in said base, said abutment member being insertable in said holes.

9. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end

of said handle operative upon movement of said handle to effect the movement of said latch, stop means comprising an abutment member fixed with respect to said base and engaging the inner end of said latch for rendering said latch immovable from its extended position, release means operative from the inside of said door for consecutively moving the inner articulated end of said latch out of engagement with said abutment member and moving the other end of said handle to effect the movement of said latch to its retracted position, and a pair of aligned holes in said base, said abutment member being insertable in said holes, said release means comprising a push bar extending through said door and engageable with the inner articulated end of said latch.

10. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, release means operative from the inside of said door for consecutively moving the inner articulated end of said latch out of engagement with said abutment member and moving the other end of said handle to effect the movement of said latch to its retracted position, said actuating means comprising

5 an extension on said handle and engageable with said latch, spring means urging said latch toward its extended position of movement, and a pair of aligned holes in said base, said abutment member being insertable in said holes.

11. A lock for a door comprising a base adapted to be secured to the outside of a door, a latch mounted in said base for back and forth movement from a retracted position within said base to an extended position with one end projecting beyond said base, said latch being articulated intermediate its ends, a handle pivotally connected to said base, actuating means at one end of said handle operative upon movement of said handle to effect the movement of said latch, stop means comprising an abutment member fixed with respect to said base and engaging the inner end of said latch for rendering said latch immovable from its extended position, release means operative from the inside of said door for consecutively moving the inner articulated end of said latch out of engagement with said abutment member and moving the other end of said handle to effect the movement of said latch to its retracted position, and a pair of aligned holes in said base, said abutment member being insertable in said holes, said inner articulated end of said latch being movable into engagement with said handle for effecting pivotal movement of the latter.
